(57) **CLAIM**

The ornamental design for a gene analysis apparatus, as shown and described.

DESCRIPTION

FIG. 1 is a front and top perspective view of a gene analysis apparatus according to the design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view taken along line 8-8 of FIG. 2; and,

FIG. 9 is a front and top perspective view showing the door in an open position.

The broken lines in the drawings depict unclaimed environmental subject matter.
